US00D902260S

(12) **United States Design Patent** (10) **Patent No.:** **US D902,260 S**
Vintzel (45) **Date of Patent:** **** Nov. 17, 2020**

(54) **AIR COMPRESSOR**

(71) Applicant: **Harbor Freight Tools USA, Inc.**,
Calabasas, CA (US)

(72) Inventor: **James Constantine Vintzel**, Jackson,
TN (US)

(73) Assignee: **Harbor Freight Tools USA, INC.**,
Calabasas, CA (US)

(**) Term: **15 Years**

(21) Appl. No.: **29/703,026**

(22) Filed: **Aug. 23, 2019**

(51) LOC (12) Cl. **15-02**

(52) U.S. Cl.

USPC **D15/9; D15/7**

(57) **CLAIM**

The ornamental design for an air compressor, as shown and described.

DESCRIPTION

FIG. 1 is a top-front perspective view of an air compressor showing my new design;

FIG. 2 is a front elevation view thereof;

FIG. 3 is a rear elevation thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom-rear perspective view thereof.

The dashed broken lines in the figures illustrate portions of the air compressor that form no part of the claimed design.

1 Claim, 8 Drawing Sheets
